UNITED STATES PATENT OFFICE.

FREDERICK W. MARTIN, OF NEW YORK, N. Y., ASSIGNOR TO ALBERT G. ELVIN, OF SOMERVILLE, NEW JERSEY.

FIRE-DOOR APPARATUS.

1,171,451.

Specification of Letters Patent. Patented Feb. 15, 1916.

Application filed September 6, 1913. Serial No. 788,387.

To all whom it may concern:

Be it known that I, FREDERICK W. MARTIN, a citizen of the United States, residing at the borough of Manhattan, in the city, county, 5 and State of New York, have invented a certain new and useful Improvement in Fire-Door Apparatus, of which improvement the following is a specification.

This invention relates to fluid pressure 10 operated apparatus for fire doors of locomotive boilers, or other furnaces, and has for its object to provide an improved apparatus of this character, in which the furnace doors are pivoted to swing laterally upward in the 15 opening movement, and to close by gravity.

The improvement claimed is hereinafter fully set forth.

In the accompanying drawings: Figure 1 is a front elevation of a fire door apparatus, 20 embodying my improvement; Fig. 2, a vertical section of the motor cylinder and piston, and showing a portion of the doors with the connections to the piston; and, Fig. 3, a detail section taken on the line 3-3 of 25 Fig. 2.

According to the construction shown in the drawings my improvement is exemplified as applied to a locomotive boiler having a door frame, 1, suitably mounted upon the 30 rear sheet of the fire box and surrounding the fire door opening. The cylinder, 4, of the door motor is mounted on the frame in a vertical position directly above the middle of the fire door opening, as indicated in Figs. 35 1 and 2. The opening is normally covered by a pair of doors, 10 and 11, which meet together substantially on the vertical center line of the opening, and are provided with arms, 10^a and 11^a, pivotally mounted on pins, 40 7 and 8, which are journaled in the frame, and on which the doors are adapted to swing laterally and vertically in the opening movement. As thus far described, the structure does not differ materially from that shown 45 and described in the prior application of Albert G. Elvin, Serial No. 781,943, filed July 30, 1913.

According to my present improvement, the pivoted arms, or portions of the doors, 50 10^a and 11^a, are provided with the respective lugs, 12 and 13, which in the normal closed position of the doors, are inclined at an angle upward toward the motor cylinder, 4, to the piston, 6, of which they are coupled

by means of the respective toggle links, 14 55 and 15, the lower end of the piston being slotted at 6^a, and provided with a pin for this connection, as shown in Figs. 2 and 3. The lower slotted end of the piston, 6, extends through the lower open end of the 60 cylinder, 4, while the upper end is closed by a cap, 5.

The piston may be operated by fluid pressure admitted through pipe, 25, as controlled by a suitable valve device, 16, operated by 65 a stem, 19, and supplied from a pipe, 24. When fluid is admitted to the cylinder, 4, the piston, 6, is forced downward, and by means of the link connections, 14 and 15, swings the doors laterally upward on their 70 pivots, 7 and 8, to the open position, as indicated in dotted lines in Fig. 2 of the drawing. In this position, the pivot points of the links fall within the straight lines from the centers of the respective pins, 7 and 8, to 75 the pivot pin on the piston when the door reaches its predetermined full open position, thus limiting the travel of the piston. When the fluid pressure is released, the doors return to closed position by gravity. By so 80 locating the toggle link connection, as above described, that each link will be in line with the pivot of the corresponding door arm in the full open position of the doors, it will be seen that the toggle connection serves as a 85 cushion and stop for limiting the movement of the piston at that point.

It will now be seen that I have provided a simple, compact, and durable form of connections between the motor piston and the 90 doors, which will operate positively, and limit the outward movement of the piston to the predetermined full open position of the doors.

Having now described my invention, what 95 I claim as new and desire to secure by Letters Patent is:

1. In a fire door apparatus, the combination of a pair of doors, each having a pivoted arm, a fluid pressure cylinder, a piston 100 therein, and a pair of toggle links connecting the piston to said arms and so located as to be in line with the pivots of the respective arms in the predetermined full open position of the doors.

2. In a fire door apparatus, the combination of a pair of doors, each having an arm and pivoted to swing laterally and verti-

cally, a fluid pressure cylinder, a piston therein, and a pair of toggle links pivotally connected to the piston and to said arms, said links being so located as to fall within 5 the straight lines from the door pivots to piston connection when the door reaches the predetermined full open position.

In testimony whereof I have hereunto set my hand.

FREDERICK W. MARTIN.
